GARAGE DOOR OPENING AND CLOSING DEVICE

Filed Nov. 6, 1924

Patented Aug. 18, 1925.

1,550,053

UNITED STATES PATENT OFFICE

HARRY WILLIAM DUDLEY ARMSTRONG, OF TORONTO, ONTARIO, CANADA.

GARAGE-DOOR OPENING AND CLOSING DEVICE.

Application filed November 6, 1924. Serial No. 748,239.

To all whom it may concern:

Be it known that I, HARRY WILLIAM DUDLEY ARMSTRONG, a subject of the King of Great Britain, and a resident of the city of 5 Toronto, in the county of York, in the Province of Ontario, Canada, have invented certain new and useful Improvements in Garage-Door Opening and Closing Devices, of which the following is the specification.

10 My invention relates to improvements in garage door opening and closing devices, and the object of the invention is to devise simple means which is operated by the weight of an automobile, for automatically 15 opening the garage doors as the automobile approaches them when entering the garage, and automatically closing such doors behind the automobile as it passes into the garage, and it consists essentially of the arrangement and construction of parts herein- 20 after more particularly explained.

Fig. 1 is a sectional perspective view of a fragmentary portion of a garage showing the run-way thereinto, garage doors, and my operating mechanism therefor, looking towards the inside of the doors.

Fig. 2 is a longitudinal sectional view through my device.

Fig. 3 is a sectional plan view on line 3—3, 30 Fig. 2.

Fig. 4 is an enlarged detail view of my garage door operating mechanism.

In the drawings like characters of reference indicate corresponding parts in each 35 figure.

1 indicates a portion of a garage floor. 2 and 3 are run-ways approaching the garage, and 4 is an inclined run-way portion which inclines upwardly as indicated at 4^x from the ends of the run-ways 2 and 3 to the bottom of the garage doors, and from thence inclines downwardly of the garage, as indicated at 4°, to the level of the floor 1, as indicated.

45 5 is the frame of the door, provided with a top plate or lintel 6.

7 is a transverse channel-way formed in the run-way 4 at each side of the door frame 5.

50 8 and 9 are channel-ways formed in the inclined portion 4^x of the run-way portion 4, such channel-ways extending from the ends of the run-ways 2 and 3 to the transverse channel 7, as clearly indicated in 55 Fig. 2.

10 and 11 are channel-ways extending in-

wardly from the transverse channel 7 to the end of the inclined portion 4° of the run-way portion 4.

12 and 13 are the doors of the garage 60 which are formed integral at their outer edges with cylindrical post members 14, which are suitably journaled in their upper and lower ends respectively in the top plate 6 and in the run-way portion 4. 65

15 is a transverse bar located in the transverse channel 7, and preferably inverted T shaped in cross section and provided at each end with an upward extension 16.

The vertical flange 15^x of the T-shaped bar 70 is provided at each side with a pair of lugs 17 and 18 respectively located in proximity to each end of the bar, and in align with the channel-ways 8 and 9, and 10 and 11. 75

19 and 20 are long tread plates which rest 75 at their outer ends on the bottom of the channel-ways 8 and 9 and normally incline upward on a level with the upper edge of such channel-ways or with the surface of the inclined portion 4^x of the run-way portion 4 80 and are pivotally mounted at their opposite ends between the lugs 18.

21 and 22 are short tread plates which rest at one end on the bottom of the runways 10 and 11, that is, at the ends remote 85 from the garage doors, and are pivotally mounted at their opposite ends between the lugs 17 of the bar 15. 90

23 are pulleys which are mounted upon the vertical members of the door frame 15 at 90 each side of the door.

24 is a cord or cable which passes round each post member 14, and is secured at one end to the outer face of each door 12 and 13, as indicated at 25, in proximity to the free 95 edge of the door, the opposite end of the rope passing over the pulley 23 and downward, the lower end being connected by a suitable link connection 26 to each upwardly extending portion 16 of the bar 15. 100

27 is a pulley mounted upon the plate 6 at each side of the door frame.

28 is a cord extending over each pulley 27 one end of which depends freely and carries a weight 29. 105

The opposite end of the cord depends downward and is connected at 30 to the cord 24.

31 is a pulley which is mounted upon each vertical member of the door frame 5. 32 is 110 a cord connected at its upper end to the cord 28, as indicated at 33. The opposite end of

the cord passes downward beneath the pulley 31 and is secured to the inner face of the door 12 or 13 intermediately of its width, as indicated at 34.

Having described the principal parts involved in my invention I will briefly describe the operation of the same.

As the automobile approaches the garage, the wheels thereof travel upon the run-ways 16 2 and 3, and on to the inclined tread plates 19 and 20, which are gradually depressed by the weight of the automobile as the wheels thereof travel longitudinally of the tread plates. By the depression of the 18 tread plates 19 and 20 the transverse bar 15 is carried downward, the ends of the tread plates 21 and 22 adjacent to the bar being also carried downward with such bar until they assume a horizontal position or 20 a position in longitudinal alignment with the depressed tread plates 19 and 20.

To perform this operation a downward pull is exerted upon the cords 24, which exerts a pull round the door post 14, round 25 which they have passed to the front side of the door, and therefore exert an outward pull upon the free portion of the door, swinging it outward to the open position indicated by dotted lines in Fig. 3.

The same operation or pull upon the 30 cords 24 exerts a pull upon the cords 28 carrying the weights 29 upward, the weight being at the limit of its upward movement when the tread plates 19 and 20 and 21 and 35 22 are depressed to the fullest extent. It will also be understood that when the weights 29 are carried upward, the other strand of the same cord 28 to which the weight is attached depending from the 40 opposite sides of the pulley 27 to the weight, travels downward, and therefore permits a slackness to occur in the cord 32, permitting the outward swing of the doors as before set forth.

When the automobile travels into the 45 garage and off the tread plates 21 and 22, such tread plates are relieved of the weight of the automobile, allowing the bar 15 to be carried upward again to its normal position by the weights 29 which descend and at the same time exert a pull upon the cords

32, pulling the doors to the closed position, the cords 24 being slackened off by means of the cross bar 15 ascending during this operation. It will of course be understood 55 that the reverse of this operation takes place when the automobile is leaving the garage.

From this description it will be seen that I have devised a very simple device for 60 opening and closing garage doors, which will be absolutely automatic, being operable by the weight of the automobile as it travels into the garage.

What I claim as my invention is: 65

In a garage door opening and closing device, the combination with the door frame comprising vertical side members and horizontal top members and substructure upon which the frame is supported, of a pair of 70 cylindrical door posts journaled at their upper ends in the frame and at their lower ends in the substructure, a door carried by each of said cylindrical door posts, a cross bar guided vertically in the substructure 75 beneath the level of the doors, a pulley mounted on each vertical of the door frame, a cord connected to each end of the cross bar and passing upward over the aforesaid pulleys around the cylindrical door posts 80 and connected at their opposite ends to the outer face of each door, a weight holding cord also connected at each end of the cross bar, a pulley mounted upon the horizontal member of the door frame at each end thereof over each of which one of the weight holding cords pass, a weight secured at the free depending end of each of such cords, and a cord connected to the weight holding 85 cord intermediate its connection to the cross bar and its carrying pulley, a guide pulley also carried by each vertical of the door frame and around which the last mentioned cord passes to its point of attachment to the inner face of each garage door, 90 and tread plates hingedly connected to each side of the cross bar over which the wheels of the automobile are adapted to travel as the automobile passes into and out of the garage. 95

HARRY WILLIAM DUDLEY ARMSTRONG.
